APPARATUS FOR HONING

Harold L. Blood, Worcester, Mass., assignor to
The Heald Machine Company, Worcester, Mass.,
a corporation of Massachusetts

Application September 15, 1936, Serial No. 100,911

7 Claims. (Cl. 51—92)

The present invention relates to an apparatus for honing and is particularly directed to a structure by which to compensate for the reduction in size of the individual honing members as a result of the honing operations.

A hone is generally made up of a plurality of honing members rigidly held to the diameter of the workpiece to be honed, and the honing members being preferably of abrasive material gradually wear away until the honing surfaces no longer properly engage the work and a compensation for wear is necessary. In certain hones as, for example, in the hone disclosed in applicant's prior copending application Serial No. 15 69,861, filed March 20, 1936, the honing members are urged resiliently against the workpiece, but in this arrangement compensation for wear on the honing members is also necessary in order that the members may engage the workpiece with sufficient pressure, especially when the expanded or operative position of the hone is limited by a positive stop. The principal object of the present invention is to provide an automatic compensation for wear on the honing members.

In the successive honing of a plurality of similar workpieces to a predetermined finished dimension, it is found that the several individual honing members making up the honing device gradually become worn away so that the honing members which are preferably urged against the workpiece by a spring or other resilient means, do not exert the desired amount of pressure on the work. A longer time for each honing operation is necessary in order to remove the proper amount of material and produce the desired finish. One of the principal objects of the present invention is accordingly to provide an automatic compensation by which to maintain the operative surfaces of the individual honing members in proper relation to the surfaces of the workpieces independently of the wear or reduction in size of the members, and independently of the number of honing operations between successive compensations.

In automatically operated honing machines where successive workpieces are mechanically placed in operative position, and where the honing operation is performed on each workpiece for the same predetermined time, it is essential that the individual honing members be in the same predetermined relation to each successive workpiece and exert the same pressure on the surfaces being honed in order that each finished workpiece may have a finished surface corresponding in appearance and dimension to each

of the other workpieces. A further object of the invention is to provide a device by which the position of the operative surfaces of the honing members may be kept uniform in relation to successively honed workpieces independently of wear on the members.

Other and further objects and advantages of the invention will appear from the following detailed description taken in connection with the accompanying drawings, in which—

Fig. 1 is a front elevation of a machine embodying the invention, parts being broken away to show the machine arrangement more clearly.

Fig. 2 is a fragmentary end view of the machine of Fig. 1, with parts broken away along the line 2—2 of Fig. 1.

Fig. 3 is a front elevation on a larger scale of one of the honing heads, partly in section, to show the construction more clearly.

Fig. 4 is a fragmentary sectional view corresponding to a part of Fig. 3, showing the position of the hones when the individual honing members have been materially reduced in size by wear.

Fig. 5 is a perspective view of the hone arbor. 25 Like reference characters refer to like parts in the different figures.

With reference to Fig. 1, the machine provides a reciprocating table 1 mounted on a base 2 and adapted to carry either the work-support or the honing device. In the construction shown, the work-support 3 is in the form of a bracket secured to the table and the honing device 4 is mounted on a bridge 5 which spans the guideways 6, Fig. 2, provided by the base 2 for guiding the movements of the table. The table is reciprocated to move the workpieces carried by the work-support axially into and out of operative engagement with the hones and this transitory movement of the table may be imparted in any desired manner, as by the use of a fluid pressure actuated mechanism of familiar construction. It is sufficient to note for the purpose of the present application that the operative position of the table with the hone engaging the workpiece to be honed is determined by dogs 7 on the table alternately engageable with a reversing lever 8 mounted on the base. The workpiece is thus given a short reciprocation relative to the hone, when in operative position, to break up any honing lines on the workpiece. In the operative position, the workpiece is in a position to extend around the individual honing members making up the hone and the inner surface of the 55

workpiece is engaged by said members, as in Fig. 1.

The work-support may be of any desired construction and the particular support shown, which is adapted for automatic discharge of the honed workpieces and loading of the un honed workpieces, has a cylindrical bore 8 corresponding in diameter to the outside diameter of the workpieces. A plurality of workpieces a and a' are placed in alignment within the bore with the leading workpiece a in a position to be operated upon by the hone. A spring-pressed latch 10 holds the workpieces against axial movement and allows the insertion of additional workpieces at the right hand end of the bore between successive honing operations, the leading workpiece a being discharged from the left hand end of the bore as a result of the loading of an un honed workpiece at the right hand end, the loading of an un honed workpiece causing an axial movement of the several workpieces within the bore 8. Any suitable automatic loading device, not shown, may be used in cooperation with the table movement for loading un honed workpieces during the run-out of the table to the right.

The machine shown is arranged to carry a plurality of work supports in alignment, with a separate honing device provided on the bridge for each work-support, as shown in Fig. 2. Since all the honing devices are similar, only one will be described.

With reference to Fig. 3, each honing device 4 comprises a housing 11 suitably secured, as by bolts 12, Fig. 2, to the bridge 5. A spindle 13 is journaled within the housing on suitable anti-friction bearings 14, and to the left hand end of the spindle is secured a pulley 15 to provide for rotation of said spindle. The right hand end of the spindle has mounted thereon a honing head 16, which may be, for example, a honing head of the general character described in applicant's copending application Serial No. 92,396, filed July 24, 1936.

The honing head has a cylindrical hub 17 which fits over the end of the spindle 13 and is in threaded engagement therewith to permit removal of the head from the spindle and substitution of a similar head of a different size or having a different type of honing stone. An arbor 18, with which the hub 17 is integral, has a plurality of radial slots 19 in each of which is positioned a bell-crank lever 20. The arbor 18 has an annular disk 21 secured thereto and one end 22 of each of the bell-crank levers is arcuate for engagement with said disk, the levers rocking about this point within the slots 19. The disk is held in position by a ring 23 which clamps the outer edge of the disk against the arbor 18, being held in position by suitable bolts 24 extending through the arbor.

Adjacent the opposite end of each bell-crank lever is positioned an arcuate protuberance 25 which engages with a correspondingly shaped recess 26 in a hone carrier 27. The latter has mounted on its outer surface a holder 28 to which is secured a honing member in the form of a block or stone 29 of suitable honing material which may be, for example, abrasive in character. The block 29 is suitably secured to the holder 28, as by adhesive, and the holder 28 is held in place on the carrier 27 by coil springs 30 and 31.

The coil springs, each of which is in the form of an annulus, extend around the honing head 29 on opposite sides of the stones 28. The spring

30 engages in notches 32 in the holders 28, the carrier 27 being similarly notched, as at 33, to cooperate with the notch 32. The spring 31 rests against lugs 34 on the holder. The coil springs not only retain the holders on the carriers, but these springs also normally tend to urge the stones and carriers radially inwardly to move the stones out of operative position and also to keep the carriers 27 in engagement with the bell-crank levers. A corresponding coil spring 35, also in the form of an annulus, is positioned in an annular groove 36 in the arbor 18 and extends around the several bell-crank levers to hold them in proper position.

Axially slidable within the arbor 18, but held against turning movement, is a spindle 37 having an arcuate shoulder 38 engageable with an arcuate protuberance 39 provided midway between the opposite ends of each of the bell-crank levers. This spindle, which is normally urged to the right, Figs. 3 and 4, as will hereinafter appear, holds the individual honing members in engagement with the workpiece a, as will be apparent, against the tension of the coil springs 30 and 31. A projecting stem 40 on the spindle has a cap 41 secured to the end thereof to protect the ends of the hone carriers and supports. The left hand end of the spindle 37 has an adjustable bolt 42 with a locking nut 43 for adjustment of the length of the spindle. Movement of this spindle to the left allows the hone to contract, and movement to the right, Figs. 3 and 4, procures expansion of the hone by a movement of the stones radially outwardly.

For actuating the hone, the main spindle 13 is hollow and has a centrally positioned rod 44 having a head 45 on the right hand end thereof engageable with the head of the bolt 42. A coil spring 46 surrounds the rod 44 and is positioned between the head 45 and a threaded collar 47 positioned within the left hand end of the spindle 13, the rod 44 being axially slidable within said collar. The left hand end of the rod 44 is threaded and engaged by threaded nuts 48 and 49, held against relative turning movement by a pin 50 and resiliently urged apart by a coil spring 51 located in recesses 52 and 53 in the nuts 48 and 49, respectively. The coil spring 51, by urging the nuts apart, creates a frictional drag to hold the nuts against turning movement on the rod 44, although allowing turning movement when a predetermined torque is applied to the nuts. The nut 49 has a cylindrical hub 54 which, when the hones are in operative position, engages with the end of the threaded collar 47 and thereby controls the expanded position of the honing stones.

The nuts 48 and 49 are movable on the rod to allow movement of the latter a greater distance to the right, Fig. 3, for expanding the hone to compensate for wear on the blocks. Referring again to Figs. 2 and 3, a collar 55 surrounds the hub 54 and is turnable on studs 56, Fig. 2, carried by an arm 57 having a slot 58 therein in which the collar 55 is located. The upper end 65 of the arm 57 is journaled on a pin 59 carried by a bracket 60, Fig. 3, secured to the housing 11, the pin 59 extending at right angles to the rod 44 to allow movement of the arm 57 in a direction for procuring axial movement of the rod 44. The lower end of the arm 57 carries an adjustable bolt 61 held frictionally against turning movement in the arm by a coil spring 62 between the end of the arm and the knurled head 63 of the bolt.

The end of the bolt is in a position for engagement with the table 1 as the latter moves into operative position, thereby procuring a clockwise swinging movement of the arm about the axis of the pin 59. This swinging movement has no effect during the normal honing operation while the hone blocks are in proper engagement with the workpiece. The nuts 48 and 49 will be normally carried to the left by the axial movement 5 of the rod 44, resulting from the contraction of the hone by entry within the workpiece so that the collar 55 will not engage the nut 49. As the blocks become more and more worn, however, the rod 44 will be urged a shorter and shorter distance to the left as a result of the entry within 10 the workpiece bore, so that the collar 55 is finally urged against the nut 49, by the movement of the table to the left, with sufficient force to release the frictional drag of the nuts 48 and 49 15 on the rod and procure a backing off of the nuts thereon, the rod rotating in the direction indicated by the arrow 62, Fig. 1, to procure this relative turning of the nuts on the rod.

In the operation of the machine, the honing head and associated parts are normally in the 25 position of Fig. 3, in which position the individual honing stones 29 are expanded to their fullest extent, as determined by the limiting nut 49 and the stones are thus in a position for engagement 30 with the tapered internal surface of the workpiece *a* as the latter is brought into operative relation. The honing members are urged outwardly by the coil spring 46, as will be apparent. The position of the honing members is controlled 35 by the nut 49, which, by engagement with the threaded collar 47, limits the outward movement of the honing members so that they are in a position for entry within the bore of the workpiece as the latter is moved from the right into 40 the operative position of Fig. 1. In Fig. 3, the workpiece is shown just before it reaches operative position during its movement to the left into operative position. The honing members are thus fully expanded as limited by the nut 49, and 45 it will be apparent that in expanded position the honing members are positioned for entry within the workpiece bore.

As the workpiece reaches the operative position of Fig. 1 and is given a slight reciprocation 50 relative to the honing members, the taper of the workpiece causes a radial in and out movement of the individual honing members which results in a slight axial reciprocation of the rod 44. At the same time that the rod is reciprocating axially, the arm 57 is oscillated through the engagement between the table 1 and the bolt 61. The oscillation of this arm has no effect whatever on the operation of the device so long as the honing members exert enough pressure on 55 the workpiece to produce the desired honing action, since the collar 55 does not engage the shoulder 64 on the nut 49. As the outer surfaces of the honing members are gradually worn away, the rod 44 must move inwardly to the right 60 more and more to hold the honing members in a position for engagement with the work and, as a result, the shoulder 64 moves nearer and nearer to the end of the collar 55 until, during a honing operation, as the arm 57 is oscillated to the left, the collar engages with the shoulder 64 with 65 sufficient pressure to procure a turning movement of the nuts 48 and 49 on the rod 44. The nuts are thus backed away slightly to allow the rod 44 to move slightly more to the right and 70 therefore to urge the honing members radially 75

outwardly. After a large number of compensatory adjustments, the honing members eventually reach the position shown in Fig. 4, where the members are substantially reduced in size by wear thereon.

It will be apparent that this compensation for wear takes place only as the honing members are worn away sufficiently to produce a firm engagement between the nuts 49 and the collar 55 and that, except when this occurs, the nuts 48 10 and 49 are frictionally held against turning movement so that no undesired compensation or backing away of the nuts will occur. It will be apparent that the hone spindle 13 must be rotating in the direction indicated by the arrow 62 in 15 order that the spindle may be turning in the proper direction to procure a backing away of the nuts 48 and 49 when desired; a left hand thread on the rod 44 would obviously allow for rotation of the spindle 13 in the opposite direction.

From the foregoing it will be apparent that the device provides for compensating for the reduction in size of the individual honing stones or members, so that the latter are always in a position to engage with the workpiece with the desired pressure, making it possible for the hone to be operative upon a plurality of successively honed workpieces without any manual adjustment and independently of the wear on the hon- 30 ing members.

I claim:

1. In a honing device, a hone comprising at least one honing member, a work-support, means for procuring a relative movement between said hone and support for bringing the hone into operative relation to a workpiece in the work-support, means for holding the honing member in operative position in the hone and means for adjusting said honing means for varying the operative position of the honing member in compensating for wear thereon, said last means being controlled by the relative movement between the hone and the work-support.

2. In a honing device, a hone comprising at least one honing member, a work-support, means for procuring a relative movement between said hone and support for bringing the hone into operative relation to a workpiece in the work-support, means for holding the honing member in operative position in the hone, means for adjusting said honing means for varying the operative position of the honing member in compensating for wear thereon, and means controlled by the relative movement between the work-support and the hone for procuring the adjustment of said adjusting means.

3. In a honing device, a hone having a plurality of honing members, a rotary spindle on which said hone is mounted, a plunger movable within the spindle for urging the honing members into operative position relative to the hone, means for limiting the movement of the plunger for controlling the operative position of the honing members, said means including a nut on the end of the plunger and engageable with the end of the spindle, and automatically operative means for procuring a slight turning movement of the nut on the plunger for varying the operative position of the honing members in compensating 65 for wear thereon.

4. In a honing device, a hone having a plurality of honing members, a rotary spindle on which said hone is mounted, a plunger movable within the spindle for urging the honing members into 70

operative position relative to the hone, means for limiting the movement of the plunger for controlling the operative position of the honing members, said means including a nut on the end of the plunger and engageable with the end of the spindle, and automatically operative means for procuring a slight turning movement of the nut on the plunger independently of the spindle rotation for varying the operative position of the honing members in compensating for wear thereon.

5. In a honing device, a hone having a plurality of honing members adapted to engage the tapered bore of a workpiece, a work-supporting member for the workpiece, means for procuring a relative reciprocatory movement between the work-supporting member and the hone for a reciprocation of the workpiece during the honing operation, means for resiliently urging said honing members against the surface of the workpiece, means for limiting the movement of the members into operative position, and means for adjusting the limiting means in compensating for wear on the members, said last means being controlled by the relative movement between the hone and work-supporting member.

10. In a honing device, a hone having a plurality of honing members adapted to engage the tapered bore of a workpiece, a work-supporting member for the workpiece, means for procuring a relative reciprocatory movement between the work-supporting member and the hone for a re-

ciprocation of the workpiece during the honing operation, means for resiliently urging said honing members against the surface of the workpiece including a plunger movable relative to the hone, means for limiting the movement of the plunger in one direction for controlling the operative position of the honing members, and means controlled by the reciprocatory movement for adjusting said limiting means when a compensation for wear is necessary.

15. In a honing device, a hone having a plurality of honing members adapted to engage the tapered bore of a workpiece, a work-supporting member for the workpiece, means for procuring a relative reciprocatory movement between the work-supporting member and the hone for a reciprocation of the workpiece during the honing operation, means for resiliently urging said honing members against the surface of the workpiece, including a plunger movable relative to the hone, a nut on the end of the plunger for limiting the movement of said plunger in one direction to control the operative position of the honing members, a rockable arm movable in response to the reciprocatory movement, and means on said arm engageable with the nut to procure a turning movement thereof for adjusting the operative position of the honing members when a compensation for wear on said members becomes necessary.

20. HAROLD L. BLOOD.
